[57] CLAIM

The ornamental design for a tape cassette holder, as shown and described.

DESCRIPTION

FIG. 1 is a perspective view of a tape cassette holder showing my new design.

FIG. 2 is a cross-sectional view taken along the line 2—2 of FIG. 1;

FIG. 3 is a reduced scale front elevational view;

FIG. 4 is a rear elevational view thereof;

FIG. 5 is a top plan view;

FIG. 6 is a bottom plan view;

FIG. 7 is a left side elevational view; and

FIG. 8 is a right side elevational view.

FIG.3.

FIG.4.

FIG.5.

FIG.6.

FIG.7.

FIG.8.
